UNITED STATES PATENT OFFICE.

ALEXANDER McDougall, OF DULUTH, MINNESOTA.

MINING APPARATUS.

No. 823,960.

Specification of Letters Patent.

Patented June 19, 1906.

Application filed January 31, 1905. Serial No. 243,582.

To all whom it may concern:

Be it known that I, ALEXANDER McDougall, a citizen of the United States, residing at Duluth, in the county of St. Louis and 5 State of Minnesota, have invented certain new and useful Improvements in Mining Apparatus, of which the following is a specification, reference being had therein to the accompanying drawings.

10 My invention relates to improvements in mining apparatus, and pertains to that class in which the ore, sand, earth, or gravel is mixed with water and the mixture conveyed by a suitable pump mounted upon a scow to 15 either a dump or stock pile, a car, a conveyer, or a washing or sorting machine, and has for its object certain improvements which will be fully described hereinafter.

In the accompanying drawings, Figure 1 is 20 a sectional view of a mine, showing the scow in side elevation and resting upon the ground during the starting of the digging of the mine. Fig. 2 is a top plan view of Fig. 1. Fig. 3 is a sectional view of the mine, showing 25 the earth moved from around the scow and the scow floating, so that it may be conveyed around to different parts of the pond. Fig. 4 is a top plan view of Fig. 3. Fig. 5 is a sectional view showing the mine of such a depth 30 that it requires several relay-pumps to raise the water, sand, and ore to the level and in which the motor on the scow is run by the power of the water-supply to the mine. Fig. 6 is a top plan view of Fig. 5. Fig. 7 is a top 35 plan view of a different arrangement of the reservoir in respect to the mine and dump.

Referring now to the drawings, A represents a small mine or pit from which the material is mined through the medium of the 40 supply of water. As shown, the water in the mine or pit is supplied through a pipe B, which is in communication with a water-supply, which is in the form of a reservoir and adapted to hold a comparatively large quantity 45 of water, and this reservoir may be supplied with water by a pipe C or any suitable or convenient means. The said pipe B is provided with a pump B', which is adapted to force the water into the pit or mine with 50 considerable force, so that the material to be mined will be loosened, and thus the same is readily withdrawn, as hereinafter more fully described. The said pump B' is driven by a motor B², which may be either an electric or steam, and the water forced into the pit or mine not only loosens the material to be

mined, but it also supplies the mine with the desired amount of water, as a certain amount of water is being at all times drawn off with the material to be mined. The pit or mine A, 60 as shown in Figs. 1 and 2, is first made of a comparatively small size, as it is gradually increased in size by the mining of the material and is also deepened; but the depth of the water therein is always kept about the same, 65 as hereinafter more fully described. I then build a scow D along the side of said pit or mine A, the same, as clearly shown, being on a level with the reservoir C and the same being started preferably in a flat or low piece of 70 ground where minerals of the desired character exist. This scow D is built very heavy, so that it will support the machinery, and when resting upon the ground, as shown in Figs. 1 and 2, will not be damaged by the vibration of the machinery thereon when in 75 said position. The said scow D is also built of a size to support the pump E and the motor F, and when the same is floated the deck of the scow is about four to six inches above 80 the water-line, so that the suction-pump carried thereby may be readily primed. The suction-pump E, as shown, is located adjacent one end of the scow and has connected thereto the downwardly-extending suction-pipe G, which is of such a length that the 85 same will extend down within a short distance of the bottom of the pit or mine, and this distance is regulated by the amount of water in the pit or mine. 90

The motor F is located adjacent the opposite end of the scow to that carrying the pump and is adapted to drive the said pump. This motor may be of any desired character, either steam, air, water, or electric, which ever may be the most convenient. Connected to the pump E is a flexible pipe H, which extends a considerable distance from the pit or mine, so that the same may be greatly enlarged during the deepening of the 100 mine. This pipe H leads to a dump H' or other place and is adapted to discharge the water and ore from the mine. The water from this dump is conveyed therefrom around the pit or mine A to the pit C by a canal I or 105 other means, and thus the same water is used over and over again where the supply of water is not sufficient to allow fresh water to be used altogether, the pipe H being flexible, so that the scow can be readily moved around the pit or mine, and thus all parts of the same 110 can be freed from the ore therein. The reser-

voir C at one side is provided with an overflow C², which would carry the water off when the same has become filled to a certain point, and said overflow being at such a level 5 that there is at all times sufficient water in the reservoir to supply the mine with sufficient water to run the same.

In the progress of operation the pit or mine becomes larger and deeper, and thus the 10 pump E has not power enough to force the water and ore therefrom to the dump, and in this case it is necessary to place a relay-pump K about midway between the scow and the dump and being placed upon a break formed 15 in the wall of the pit. The said pump is operated by a motor K, which is of the same character as that of the pump E in Figs. 1, 2, 3, and 4, and this is preferably of the electric type. When the pit or mine has become so 20 deep that the pump E has not power enough to force the ore up to the relay-pump K, another pump L is placed intermediate the pump E and pump K on a ledge in the pit or mine, and said pump is driven by the motor 25 L'. In this way it will be seen that the ore and water are pumped from the pump E on the scow to the pump L, from the pump L to the pump K, and the pump K forces it to the dump. It is understood as the pit or mine 30 deepens the number of pumps may be increased, thus forcing the water and ore to the dump.

In the modification shown in Figs. 5 and 6, instead of using other motor power for operating the pump E on the scow, I connect a 35 pipe M therewith, which has its upper end extending within the reservoir C considerably below the water-line thereof, and thus by force of gravity the water will flow with 40 great force to the motor F, and thus the motor is adapted to operate the water and ore suction-pump E. The exhaust-water from the motor is so arranged that it tends to loosen the sand and ore in the same way in 45 which this is accomplished in Figs. 1, 2, 3, and 4.

In using water as the motive power in operating the pump E on the scow there will 50 more water enter the pit or mine than is carried off with the ore and sand, and thus the water in the pit would gradually fill up the same, so that the pipe G would not extend near enough to the ore and sand, and thus nothing but water would be excavated. In 55 order to keep the water in the mine at the desired level, so that the suction-pipe G will be approximately the required distance from the ore at the bottom of the mine, I provide a pump N on a ledge of the mine on the side 60 adjacent the reservoir, and extending into the water is a suction-pipe n, which has its upper end communicating with the pump, and extending from said pump to the reservoir is a pipe n', which conveys the water from the 65 pump to the reservoir, and thus when the

water in the pit or mine becomes too deep for the suction-pipe G to act upon the ore the pump N is operated through the medium of the motor N' and continued to work as long as the water is too deep, and it will be found necessary to continue the slow running of said pump to keep the water at the desired depth, as there is more water entering through the pipe M than is being drawn off by the pump E, as heretofore described. 70

In the arrangement shown in Fig. 7 instead of placing the supply-reservoir C on the opposite side of the mine, as shown in the first five figures, I place the same on that side of the mine on which the dump H' is arranged, 75 thus shortening the canal I and necessarily decreasing the cost of constructing the mine. In this form the pipes H, B, and C' all have the same relative operation as those shown in the first six figures. 80

Having thus described my invention, what I claim, and desire to secure by Letters Patent, is—

1. A mining apparatus comprising a mine having water therein, a scow floating therein, 90 a suction-pump carried by the scow, a pipe leading from the pump into the water, a partly-flexible pipe leading from the pump to the dump, a reservoir receiving the water from said dump, a pipe in communication 95 with the reservoir and the pump on the scow and adapted to operate the pump, and a pump adjacent the pit and adapted to draw the water from the mine and discharge it into the reservoir. 100

2. A mining apparatus comprising a mine having water therein, a scow floating therein, a suction-pump on said scow, a motor carried by the scow for operating said pump, a suction-pipe communicating with the pump 105 and extending into the water below the scow, a flexible pipe communicating with the pump on the scow and communicating with two or more relay-pumps between the scow and the dump, a reservoir located near the mine and 110 the dump, a canal conveying the water from the dump to the reservoir, a pipe leading from the reservoir and discharging water to the motor on the scow for operating the same, the exhaust-water loosening the sand and 115 ore, a pump adjacent the water in the mine and adapted to force the water from the mine to the reservoir for keeping the water in the mine a determined depth. 120

3. A mining apparatus comprising a mine having water therein, a scow floated by said water, a pump upon said scow for drawing the said ore and gravel from the mine, a number of relay-pumps, each receiving the water, ore and sand from the adjacent pump, and carrying the same to the dump, a reservoir adjacent said dump and adapted to receive the water therefrom, a water-supply for said reservoir, a pipe leading from the reservoir and adapted to operate the pump carried by 130

the scow, and a pump for forcing a portion of the water directly from the mine back to the reservoir.

4. A mining apparatus, comprising a mine having water therein, a scow within said mine, a suction-pump mounted on said scow, a motor carried by the scow for operating the pump, a water-supply for said mine and adapted to operate said pump and loosen the ore within the mine, and a pump for forcing a portion of the water directly from the mine,

whereby the water in the mine is kept at a certain depth so that the suction-pump carried by the scow may work from the bottom of the mine. ¹⁵

In testimony whereof I affix my signature in presence of two witnesses.
